UNITED STATES PATENT OFFICE

2,454,634

ELECTROMAGNETIC CIRCUIT

George D. Craig, II, Flushing, N. Y.

Application August 9, 1945, Serial No. 609,893

6 Claims. (Cl. 172—281)

1

This application for patent describes my invention relating to electro-magnetic circuits. The invention is illustrated as applied in one embodiment to the operation of a planing device but it is to be specifically understood that this is merely an illustration of one use of my improved electro-magnetic circuit.

For many purposes and in many operations, it is desirable to have available and to utilize electrical currents, the characteristics of which vary according to a regular, recurring, pattern with the passage of time. Thus, the voltage-time characteristic, the current-time characteristic, or the phase-time characteristic, or any combination thereof, may desirably be caused to follow a definite pattern, which pattern is repeated over and over again during the operation of the device. When the operation of the device is to be changed, or when the current supplying circuit is to be used with a different device, it is often desirable to change the recurring pattern to adapt it to the changed operation or the different mechanism.

The present invention is directed to the provision of means to generate or control an electric current or currents, so as to provide an electric current or currents, the characteristics of which follow a predetermined, recurring, time pattern, and which predetermined, recurring, time pattern can be readily changed or adjusted.

The output of an electromagnetic circuit constructed in accordance with this invention is an electrical current, one or more characteristics of which vary in accordance with time and in accordance with a recurring pattern. The electromagnetic circuit of this invention is so arranged that it can be expediently adjusted to change the pattern so that a current of the desired pattern of characteristics can be supplied for any one of the great number of purposes.

For example, in operating machine tools, such as planers and shapers, it is often desirable to have the machine travel relatively slowly during the cutting stroke and then travel relatively rapidly during the return stroke. Well known means are available for controlling the speed of such a device in accordance with the voltage of a current supplied to a control device, and by means of the present invention a current can be supplied to the control device, the voltage of which will vary in accordance with time, just as it is desired to vary the speed of operation of the planer or shaper. Thus, by the use of the present invention, the operation of a planer or shaper may be expediently controlled to cause it

2

to operate slowly during the cutting stroke and rapidly during the return stroke.

To anyone versed in the electro-mechanical art, many constructional schemes will become obvious for obtaining the objectives of this invention. Therefore, it is to be expressly understood that my idea is not limited by physical construction inasmuch as the objectives outlined in this application may be obtained with a device or devices assuming many combinations of the structural features of generators (including permanent magnet type), motors, self-synchronous devices, toroidal wound devices, variable transformers, etc., wherein a single unit consists of at least two elements such as a stator and a rotor, where said rotor and stator elements may have a single phase winding or a plurality of phases and poles, where said stator and rotor of each single unit may have either or both elements constructed with a single phase winding or a plurality of phases and poles, where either of said elements is capable of being positioned or rotated with respect to the other and where one or more coils of any element may be energized from an electrical source, said source being direct current, single or multi-phase pulsating or alternating current.

The figures of this application show elementary schematic electrical and mechanical connections of two or more devices which when properly manipulated give one or more voltage changes definitely related to one another and each following a mathematical transcendental function.

One of the objects of my invention is, therefore, the production of electrical currents having characteristics which vary in accordance with a recurring pattern with respect to time, which pattern can be controlled as desired.

A further object of the invention is a method of producing and controlling electrical currents so as to give them characteristics which follow a definite recurring pattern with respect to time and utilizing such electrical currents for the operation and/or controlling of operations in any desired field.

A further object of the invention is the provision of means and/or machines for producing and controlling electrical currents having designated characteristics.

One of the features of my invention is the provision of a transformer apparatus through which an alternating current (or if desired a direct current) may induce a current having a characteristic which may be controlled to take any shape.

Further objects and features of my invention will be apparent from a reading of the subjoined specification and claims in connection with the accompanying drawings illustrating several specific embodiments of my invention.

In the drawings:

Figure 1 is a diagrammatic view illustrating one embodiment of my invention as applied to the operation of a planing device;

Figure 2 is a diagrammatic illustration of another embodiment of my invention, in which the induced currents are 120° apart;

Figure 3 is a diagrammatic illustration of a third embodiment of my invention which is similar to that of Figure 2, except that the two rotors illustrated are geared to rotate at a rate proportional one to the other;

Figure 4 is a diagrammatic view of another embodiment of my invention in which there are provided three rotor elements and three stator elements, and in which the current of each of the rotor elements and of each of the stator elements is two phase;

Figure 5 is a graph disclosing the resulting or output voltage curves of the currents induced in the stator elements by the circuit illustrated in Figure 2;

Figure 6 is a straight line graph showing the resulting voltages induced in the stator circuit by the arrangement disclosed in Figure 2, and

Figure 7 is a graph illustrating the resulting voltages induced in the stator circuit by the arrangement shown in Figure 3.

Referring specifically to the drawings, it may be seen that I have illustrated in Figure 1 an arrangement in which alternating current is supplied from a suitable source through inlet leads 11 and 12 connected to winding 13 of rotor element 14 and to winding 15 of rotor element 16. Associated with rotor element 14 is a stator element illustrated by coil 17 and associated with rotor element 16 is a stator element illustrated by coil 18. The current induced in the circuit 19 which includes the stator elements 17 and 18 controls the operation of a motor control 21, which controls the speed at which an electric motor 24 is operated, in accordance with the voltage or current in the circuit 19. The motor control 21 may comprise any of the usual control elements, such as Selsyn motors, thyratron tubes and the like. These are all well known and are not described in detail here. The motor 24 is arranged to drive a belt 25 and a pinion 26, which in turn operates the movable element 27 of a planer 28. The voltages induced in the circuit 19 are controlled by the position of the rotors 14 and 16 so that when the movable element 27 is moving forward in its operating stroke it moves at a relatively slow speed so that the shaving or planing operation may be efficiently accomplished. However, when it is moving on its return stroke the voltages induced are such that the motor 24 is operated at a higher rate of speed and the movable element 27 is returned at a relatively high speed.

The control of the voltages induced in the circuit 19 is accomplished in the following manner: The current supplied through the wires 11 and 12 to the windings 13 and 15 is alternating current and thus creates in the coils 17 and 18 an alternating current induced thereby. If the rotors 13 and 15 were properly positioned angularly and held stationary, the phases of the induced currents synchronized, the current induced in the two windings 17 and 18 would be sub-

stantially the same. In my device the rotor 16 is held stationary while the rotor 14 is rotated relative to the stator coil 17. Thus, at times the current induced in the coil 17 is in phase with the current induced in the coil 18, while at other times the currents induced in said coils conflict with each other and thus decrease the voltages induced. Thus, I may by rotating the rotor 14 at proper speeds, cause the induced current to assume a voltage characteristic such that it controls the flow of current to operate the motor 24 during the shaving stroke at the desired speed and on the return stroke operates it at a different, relatively swifter speed. The rotor 16 may be rotated by any conventional means such, for example, as a small electric motor connected to the rotor through suitable gearing. The other rotor 16 may be held stationary, and its position adjusted manually from time to time to adjust the pattern of the current output of the control device or may, as indicated in some of the following examples, be rotated by an independent source of power, or by being geared to the first-mentioned rotor 14. Since numerous well known means are available for rotating either or both of the rotors, it is not desired to limit the present application to the use of any specific means for rotating or holding stationary, or adjusting the position of, either of the rotors.

I will now refer to Figures 2, 5 and 7 for a more detailed description of the possibilities of controlling the induced currents.

Figure 2 shows two units electrically connected so that three output voltages V_1 , V_2 and V_3 (120° apart) vary in magnitude and phase when rotor #1 is positioned and held stationary while rotor #2 is positioned or made to turn at any given rate. The results of V_2 from this action may be found plotted on the graphs of Figures 5 and 6. V_1 and V_3 would, of course, be positioned 120° either side of V_2 . It may be seen that in Figure 2 I have provided a rotor 31 and a rotor 32, these rotors having windings 33 and 34 respectively which are connected in electrical circuits 41 and 42 to which alternating current is supplied by leads 43 and 44. These rotors 31 and 32 are single phase, salient pole rotors. The alternating current supplied through leads 43 and 44 causes electrical currents to be generated in the stator windings. The rotor 31 is intended to remain normally stationary but may be set at any desired angle relative to the stator element. The rotor 32 on the other hand is intended to be rotated continuously during operation so as to produce the desired voltage wave throughout its operation.

The stator elements associated with the rotor elements 31 and 32 are designated 45 and 46, respectively. Each stator is three phase and two pole and they each have three windings designated 47, 48 and 49 and 51, 52 and 53. Windings 47 and 57 are connected in series as are windings 48 and 52, and windings 49 and 53. Each of these pair of windings is spaced 120° on the stator element so that if the rotor elements 31 and 32 were positioned so as to generate electric voltages in the stator elements in phase, the voltages induced in 47, 48 and 49 would each reinforce or build up the voltages induced in 51, 52 and 53, respectively. Inasmuch, however, as rotor 31 is maintained stationary while rotor 32 is rotated, the voltages induced will vary, depending upon the setting of rotor 31 and upon the speed of rotation of rotor 32. For instance, with settings of rotor 31 at 30° , 45° , 60° , 75° and 90° , the voltages induced

in each of the sets of windings of the stator elements 45 and 46 will follow the curves disclosed in Figure 5, the equations for which are

$$V = -2E \sin \frac{\theta_2 + \theta_3}{2} \text{ and } \sin \frac{\theta_2 - \theta_3}{2} = V_2$$

The curves disclosing the resulting voltages induced in stator elements 31 and 32 are also plotted on straight line coordinates in Figure 6, wherein the curves designated as 0, 30, 45, 60, 75 and 90, each represent the voltage induced when the rotor 31 is set with an angle of 0, 30, 45, 60, 75 and 90°, respectively.

In Figure 3, I have shown another embodiment of my invention. Figure 3 is identical to Figure 2, except that rotors #1 and #2 are mechanically connected to one another (e. g. geared together). Results of V_2 for this set-up may be found plotted on the graph shown in Figure 7. It is to be noted that the resulting transcendental function is dependent upon the gearing ratio or the relative angular movement of one or more rotors with respect to another rotor or rotors wherein the rotors are elements of separate units or devices consisting of two elements as heretofore explained.

In the specific arrangement illustrated in Figure 3, the rotors 131 and 132 are so geared to each other so that rotor 132 is rotated at a speed of rotation that is twice the speed of rotation of unit 131. Stator elements 145 and 146 correspond substantially to stator elements 45 and 46, the combined voltages induced being led by means of connections 154, 155 and 156 to devices which it is desired to operate by means of the induced currents.

The currents and voltages which are induced in the circuits 154, 155 and 156 are each similar to each other, but are spaced at intervals of 120° each. Their characteristics are shown in the curves of output voltage V_2 of Figure 7, using the circuit of Figure #3 and using a gear ratio between the two rotor elements of 2 to 1. It is to be understood that any desired gear ratio may be used or any desired mechanical connection between the two rotors 131 and 132 may be provided so that any desired relation of movement between the two rotors may be accomplished, and thus any desired characteristics of the output voltages may be secured.

In Figure 4 I have disclosed still another embodiment of my invention. This figure shows an extension of the basic idea wherein there are three units with electrical connections similar to those in Figures 2 and 3 but with non-salient pole rotors wound multi-phase and energized from a multi-phase source. In this embodiment two phase alternating current is supplied through leads 161, 162 and 163 to rotor elements 164, 165 and 166. Each of these rotor elements includes two coils, such as 164a and 164b, 165a and 165b and 166a and 166b and similarly, the stator elements 167, 168 and 169 each have two coils such as 167a and 167b, 168a and 168b and 169a and 169b. The induced voltages of the stator elements 167, 168 and 169 are thus controlled (a) by the fact that the rotor elements 164, 165 and 166 have two phase windings (b) by the fact that the stator elements 167, 168 and 169 have two phase windings (c) by the setting of rotor element 165 (d) by the setting of rotor element 166. These induced voltages for phase 1 are led off to the work to be performed by a circuit including leads 171, and 172, and those induced by the other phase

of the stator winding are led off by a circuit including lead wires 173 and 174.

It is to be understood that while I have disclosed my invention as designed to use alternating current, it is possible also in certain cases to use direct current. For example, referring to Figure 1, wherein the rotor 15 is maintained stationary, while the rotor 13 is rotated, it may be seen that with the use of direct current in rotor 13, an alternating current would be induced in the stator element 17 which would pass through the stator coil 18 and thus coming under the influence of the field of stationary rotor 15 having direct current supply thereto would modify the characteristics of the voltages induced in the circuit including the coils 17 and 18 arranged in series.

Thus it is to be seen by anyone versed in the electrical art that an infinite number of voltage patterns may be obtained with two or more units mechanically and electrically connected as shown in Figures 1, 2, 3 and 4, and their rotatable elements manipulated by data sources.

The scope of this invention may be appreciated from the following examples of diversified objectives:

1. The formation of voltage output patterns following, e. g.: the polar equation

$$r = -2E \sin \frac{\theta_2 + \theta_3}{2} \sin \frac{\theta_2 - \theta_3}{2}$$

$r = E \cos \theta_2 - E \cos (\theta_1 + \alpha)$ and its derivatives where E =maximum voltage of one phase of one device, α is the angular displacement of rotors #1 and #2, θ_1 and θ_2 are angular displacement of rotors #1 and #2 (as seen in Figure 2) from their respective working secondary or stator phases, and the values of α , θ_1 , θ_2 and θ_3 are infinite in number. ($\theta_3 = \theta_1 + \alpha$.)

2. To provide a variable voltage source having a variable phase relation with respect to the primary or energizing voltage source wherein the phasing angle is a function of unit rotor angle.

3. To provide a means of varying the phase angle and magnitude of the induced (output) voltage from 0 to 360° or more.

4. To provide a means for transforming uniform mechanical motion into variable motion through utilization of circuits such as those shown in Figures 1, 2, 3 and 4 in a manner analogous to mechanical cam operation.

5. To provide means for converting mechanical motion into an infinite number of electrical or mechanical quantities each following a definite transcendental function and then repeating said pattern after desired intervals of time.

6. To provide a means for translating mechanical data into electrical data, the latter bearing definite relationship to transcendental functions.

7. To provide a means for conveying and converting data remotely into an infinite number of desired transcendental functions.

8. To provide an adjustable timing source through the interim of adjustable voltage phasing and/or magnitude.

9. To provide a means of introducing corrective measures in an electrical or mechanical device.

10. To provide means for solving given transcendental functions involving elapsed time, voltage magnitude and angular motion.

11. To provide a means for producing mechanical power output with variable speed, controlled through loading of induced voltage windings.

12. To provide means for producing mechanical power output with self-synchronizing action

of two or more rotatable elements through loading of induced voltage windings.

These various objectives present a general picture of the numerous applications and innovations of this invention and in view of its capacity said aims and objectives set forth are not to be construed as limiting the scope of the basic idea.

It is to be understood that the above described embodiments of my invention are for the purpose of illustration only and various changes may be made therein without departing from the spirit and scope of the invention.

I claim:

1. A device for producing an electrical current, the characteristics of which vary in accordance with the passage of time in a fixed recurring, non-sinusoidal pattern that comprises at least two inductances connected in series, means for producing an electromagnetic field, means for producing relative cyclical movement between said field and one of said inductances so that said inductance is cyclically acted upon by said field and means for producing a second electromagnetic field independent of the first and applying said second electromagnetic field to another of said inductances.

2. A device as defined in claim 1 further characterized in that means are also provided for relatively moving said second electromagnetic field and the inductance upon which it acts.

3. A device as defined in claim 1 further characterized in that means are provided for relatively moving in a cyclic manner, said second electromagnetic field and the inductance upon which it acts.

4. A device as defined in claim 1 further characterized in that means are provided for adjusting the relative positions of said second electromagnetic field and the inductance upon which it acts.

5. A device as defined in claim 1 further characterized in that means are provided to produce relative movement between said second electromagnetic field and the inductance upon which it acts in a predetermined relation to the relative movement between said first electromagnetic field and the inductance upon which it acts.

6. A device as defined in claim 1 further characterized in that means are provided for producing relative cyclic movement between said second electromagnetic field and the inductance upon which it acts, and in which the means for producing the relative movement between the first field and inductance and the means for producing the relative movement between the second field and inductance are geared together so that the two movements bear a constant relationship.
